UNITED STATES PATENT OFFICE.

GEORGE N. DOWNS, OF CHICAGO, ILLINOIS, ASSIGNOR TO THE TROY LAUN-
DRY MACHINERY COMPANY, OF TROY, NEW YORK.

CENTRIFUGAL MACHINE.

SPECIFICATION forming part of Letters Patent No. 380,555, dated April 3, 1888.

Application filed July 11, 1887. Serial No. 243,951. (No model.)

To all whom it may concern:

Be it known that I, GEORGE N. DOWNS, of Chicago, in the county of Cook and State of Illinois, have invented certain new and useful 5 Improvements in Centrifugal Machines; and I do hereby declare that the following is a full, clear, and exact description thereof, reference being had to the accompanying drawings, and to the letters of reference marked thereon, 10 which form a part of this specification.

This invention relates to an improvement in centrifugal machines or devices for extracting by centrifugal action fluid from solid substances.

15 The invention consists in the matters hereinafter described, and pointed out in the appended claims.

The machine herein shown as embodying my invention is intended more especially for 20 use in laundries, for the purpose of extracting water from clothing or other articles preparatory to drying the same.

The invention may be more readily understood by reference to the accompanying drawings, in which—

Figure 1 is a side view of a machine constructed in accordance with my invention. Fig. 2 is a sectional plan view of the same, taken upon line $x\ x$ of Fig. 1. Fig. 3 is a central vertical section of the same, taken upon line $x\ x$ of Fig. 2. Fig. 4 is an enlarged detail section of the shaft-support and pulley shown in Fig. 3. Fig. 5 is a detail sectional plan view taken upon line $z\ z$ of Fig. 3. Fig. 35 is a detail section taken upon line $y\ y$ of Fig. 3. Fig. 7 is a detail section taken upon line $x\ x$ of Fig. 4. Fig. 8 is a detail section of one of the spring-connections between the base of the machine and the arm attached to the shaft- 40 bearing. Fig. 9 shows a somewhat different form of the spring-connection illustrated in Fig. 8. Fig. 10 illustrates a modification of the actuating devices for the brake-shoe.

As illustrated in the said drawings, A is a circular tank or receptacle of the machine, which is supported by means of standards A' 45 from a metal bed-plate, A².

B is the revolving perforated cylinder of the extractor, which is located within the receptacle A, and within which the articles from which the water is to be extracted are placed.

Said perforated cylinder B is mounted upon the upper end of the vertical shaft C, passing through a central aperture, a, in the bottom of the receptacle A, and having bearings at 55 its lower end in a long bearing-box, D. This bearing-box is pivotally supported upon the bed-plate A², and is held in a vertical position by means of a plurality of rigid arms, E E E E, rigidly attached to the box and connected 60 at their free ends with the bed-plate A² by spring-connections F F F F, which are so adjusted as to hold the shaft C normally vertical, but which are adapted to yield, so as to allow the shaft and the cylinder carried thereon 65 to seek and maintain an axis of rotation passing through its center of gravity.

G is a driving-pulley affixed to the shaft C, said pulley being made hollow and arranged to extend over or around the pivotal support 70 of the shaft C, so that the bearing-surface of the pulley is brought centrally opposite the pivotal axis of the bearing D. The object of this construction is to bring the pressure of the driving-belt against the pulley equally on 75 either side of the pivotal axis of the said bearing, so that such pressure of the driving-belt will have no tendency to throw the shaft out of its vertical position.

The pivotal connection between the bearing 80 D and the machine-frame is herein shown as formed by a ball-and-socket joint located between the ends of a long bearing arranged to extend both above and below the pivotal point of the said joint. For this purpose the said 85 bearing D consists of a metal sleeve or box, D', provided at its middle part with a spherical enlargement, d, the exterior surface of which is fitted within a correspondingly-shaped socket, h, formed in a tubular standard, H, 90 bolted to the bed-plate A². The socket h is shown as divided horizontally into two parts, forming a removable cap, h', to allow the insertion of the spherical enlargement in the socket. The arms E E are in this construction 95 rigidly attached to the lower end of the sleeve D' below the bearing aperture therein, said arms being constructed to extend outwardly through lateral openings h² h² in the tubular bracket H. This construction obviously enables the bearing for the shaft to be made very 100 long vertically, while at the same time giving

a compact form to the pivotal joint, enabling it to be placed within the rim of a belt-pulley of relatively small diameter.

The device shown in the drawings embraces an improved construction in the bearings for the shaft and oiling devices within the bearing-box D', as follows: Said box D' is made somewhat larger in the interior diameter than the exterior of the shaft, and within the said box is placed a tubular lining, D², which will commonly be made of brass or other soft metal suitable for bearings. The lining D² is, as more clearly shown in Fig. 7, provided with longitudinal grooves d'd' in its exterior surface, and is provided with perforations d'd', leading from said grooves inwardly to the bearing-surface of the sleeve. At its middle part, within the spherical enlargement d, the box D' is provided with a recess or chamber, d³, which forms a reservoir for oil, and communicates with the vertical passage formed by the grooves d'd' in the manner clearly shown in Fig. 4. The oil for lubricating the bearing is inserted within the chamber d³, fills the vertical passage formed by the grooves d', and passes from said recess and vertical passages through the perforations d' to the contact-surfaces of the bearing.

For lubricating the bearing-surface between the box D' and the socket h, one or more openings, d⁴, may be formed in the wall of the chamber d³, as clearly shown in the drawings, Fig. 4. The grooves d'd' preferably terminate short of the ends of the sleeve D², so that the end portions of the said sleeve fit tightly the inner surface of the box, in the manner clearly shown in the drawings. For taking the end-thrust of the shaft, a separate step or bearing block, D⁵, will commonly be fitted within the lower part of the lining, so as to rest against the bottom of the aperture in the bearing-box, in the manner clearly shown in the drawings.

For conveniently supplying oil to the bearing, I have herein shown a bent tube, D⁶, as inserted through the bearing D', so as to enter one of the vertical passages formed by the grooves d', said tube being extended outwardly through a suitable opening in the bracket H and beneath the edge of the drive-pulley G, and bent at right angles and carried upwardly outside of the pulley to a point near the level of the top of the bearing.

The spring-connecting device F, uniting the outer ends of each of the arms E E with the bed-plate A² of the machine, consists, as herein shown, of a metal yoke, F', connected by a pivot, f, at its lower end with the bed-plate, and attached at its upper ends to a centrally-apertured plate, F², together with a rod, F³, pivoted to the end of the arm E and inserted through the plate F², and provided at its lower end with a disk, f', between which disk and the plate F² is located a coiled spring, F⁴. The disk f' is constructed to slide on the rod F³, and is held thereon by means of a nut, f², which may be adjusted upon the rod for the purpose of giving greater or less tension to the spring, as desired. By adjusting the ten-

sion of the springs F⁴ F⁴, belonging to the several arms, the shaft and perforated cylinder may be sustained in position most favorable for running with uniformity and smoothness. The plate F² and yokes F' are herein shown as arranged to form part of a cylinder, F⁵, which serves to form a guide for the disk f' and to cover and hold in place the spring F⁴. 75

In Fig. 9 I have shown a somewhat different construction in the spring-connection F, in which the latter is provided, in addition to the spring F⁴, with additional springs, F⁶ F⁷, made shorter than the spring F⁴, so that 80 they do not come into action unless the said spring F⁴ is considerably compressed. The purpose of said springs F⁶ F⁷ is to hold the shaft from extreme deviation from the vertical, in case an exceptionally-heavy load is 85 thrown on one side of the revolving cylinder.

It has been proposed heretofore to hold the vertical shaft in an extractor in a vertical position by means of springs acting directly against the shaft-bearing and adapted to yield 90 to allow the shifting of the shaft laterally when the movable part of the extractor is in rotation, so as to allow the extractor to rotate about its center of gravity.

By the construction above set forth, in which 95 radial arms are attached to the said bearing, and spring-connections are located between the ends of said arms and the machine-frame, I am enabled to adjust the shaft much more accurately and control its motion with much 100 more certainty, for the reason that in this construction the power of the springs is applied at a point remote from the center of movement of the shaft, and at which a considerable leverage is gained. 105

It sometime occurs in the use of a machine in which the rotating cylinder is mounted upon a shaft supported at its lower end only that by the breakage of parts or for some other reason, the cylinder and upper end of the 110 shaft, when in rapid rotation, are thrown laterally against the edge of the aperture a in the outer receptacle, A. The contact of the shaft with the edge of the said opening at such time is likely to cause great injury to, if 115 not total destruction of, the machine; and to obviate the liability of injury in a case of this kind I place around the margins of the said hole a freely-rotating ring, which is mounted in such manner as to engage the shaft in case 120 the latter is thrown sidewise, the rapidly-rotating shaft in this case serving to turn the ring without having any other effect on the machine.

As illustrated in the accompanying drawings, I is the ring above referred to, which is placed within an annular rabbet or recess formed upon the bottom wall of the receptacle A adjacent to the opening a and covered with a plate, I', placed over the said recess. For 125 the purpose of sustaining said ring so that it may revolve with little friction, I place between the ring and its supporting-surface a series of anti-friction rollers, i', and I sustain 130

the ring from horizontal movement by a series of anti-friction rollers, i^2 , rolling against the outer surface of the ring and against the inner surface of a vertical flange, a' , upon the upper 5 surface of the bottom of the receptacle. Said anti-friction rollers i^2 are preferably located within an annular groove, i^3 , formed in the under surface of the ring I.

The rollers i^2 may be conveniently sustained 10 upon the flat top of a rib or flange, a^2 , located within the flange a' , in the manner shown, the said rollers being held from displacement by means of suitable annular bearing-surfaces upon the under surface of the plate I' in the 15 manner shown in the drawings.

The cylinder B of the extractor is herein shown as constructed in a manner heretofore well known, the bottom of said cylinder being formed by two convex plates, $b b'$, secured to 20 a flanged sleeve, B' , placed around the upper part of the shaft, and held thereon between a suitable collar or shoulder, c , and a nut, c' , placed upon the upper threaded end of the shaft, and serving to hold the said sleeve B' 25 rigidly upon the shaft. Said cylinder B is provided at its upper edge with an inwardly-extending flange, B^2 , while the outer receptacle, A, is provided with a similar flange, A^3 , arranged in the manner heretofore well known 30 in devices of this character.

J J, Figs. 1 and 2, indicate two guide-pulleys for the driving-belt, said guide-pulleys being mounted upon arms $j j'$, attached to a standard, J' , located at one side of the machine-frame, the pulleys being arranged horizontally 35 opposite the main driving-pulley G, in the manner shown in the drawings. K is a brake-shoe arranged to act upon the belt-pulley G at the side of the latter nearest the guide-pulleys 40 J J, so that said shoe will not interfere with the belt and will act to thrust the pulley in a direction opposite to that which it tends to move by the pull of the belt, so that the pressure produced by the application of the brake-shoe will have little tendency to disturb the 45 equilibrium of the revolving part of the extractor. A brake-shoe thus located may be sustained and operated in any one of a number of ways. As herein shown, it is supported 50 upon vertical rods $k k'$, which are pivoted at k' to the bed-plate of the machine.

In Figs. 1 and 2 the devices for actuating the brake-shoe consist of toggle-arms $L L'$, which are pivoted to the brake-shoe and one 55 of the standards A' of the machine-frame, and are pivotally connected at their inner or adjacent ends with a vertical bar, M, the lower end of which is pivoted to the end of a horizontal arm, M' , upon a rock-shaft, M^2 . Said rock-shaft is provided with suitable means for actuating it, herein shown as consisting of a foot-lever, M^3 . In connection with a brake-shoe 60 thus arranged, I provide a spring holding the brake-shoe normally clear of the driving-pulley, a spiral spring, M^4 , being herein shown as applied between the lever M^3 and one of the frame-standards A' for this purpose.

In Fig. 10 is shown a somewhat different form of brake device, more particularly adapted for use in the smaller sizes of machines, 70 where there is little room within the frame. In said Fig. 10, N is a bell-crank lever, which is pivoted at n to the standard A' , and the upper end of the vertical arm of which is connected by a rod, N' , with the brake-shoe K. The 75 horizontal arm of said bell-crank lever is connected by a pitman, n' , with the horizontal arm N^2 of a rock-shaft, N^3 , arranged in the same manner as the rock-shaft M^2 shown in Figs. 1 and 2. 80

I claim as my invention—

1. The combination, with a revolving cylinder and a vertical supporting-shaft therefor, of a step or bearing engaging the lower end of the said shaft and affording the sole means 85 of supporting the same, said bearing being connected with the machine-frame by a universal joint, rigid arms attached to the said bearing and extending outwardly from the same, and spring-connections between the outer ends of said arms and the machine-frame or other stationary support or supports, substantially as described. 90

2. The combination, with a revolving cylinder and a vertical supporting-shaft therefor, 95 of a step or bearing engaging the lower end of the shaft and affording the sole means of supporting the same, said bearing being connected with the machine-frame by a universal joint, rigid arms attached to the said bearing, 100 and spring-connections between the outer ends of the arms and the machine frame embracing devices for adjusting the tension of the springs, substantially as described.

3. The combination, with a revolving cylinder and a vertical shaft supporting the same, of a step or bearing for the lower end of the shaft, said step or bearing being provided with an exterior spherical enlargement, a support for the bearing provided with a socket at 110 its upper end to receive said spherical enlargement, a pulley attached to the shaft above the bearing and extending downwardly outside of said bearing and around the support thereof, radial arms rigidly attached to said 115 bearing below the said spherical enlargement and socket, and spring-connections between the outer ends of said arms and adjacent stationary supports, substantially as described. 120

4. The combination, with a revolving cylinder and a supporting-shaft therefor, of a step or bearing for the lower end of the shaft, consisting of a box, D' , provided with a central oil-recess, and a lining, D^2 , inserted in said box and passing through the oil-recess, said 125 lining being provided with exterior longitudinal grooves and with perforations extending from the said grooves to the bearing-face of the lining, substantially as described.

5. The combination, with a perforated revolving cylinder of a centrifugal extractor, a vertical shaft supporting the same, and a bearing for the shaft constructed to allow inclination of the latter, of an exterior shell or re- 130

ceptacle provided with an aperture in its bottom through which said shaft passes, and a freely-rotating ring larger than the shaft surrounding said shaft and sustained upon the receptacle adjacent to said aperture, substantially as described.

6. The combination, with a revolving cylinder of a centrifugal extractor, a shaft for supporting the same, a bearing for the shaft constructed to allow inclination of the latter, and an exterior shell or receptacle provided with a central aperture in its bottom, of a

freely-rotating ring larger than the shaft, mounted upon said receptacle adjacent to said opening, and anti-friction rollers sustaining the ring and holding it from lateral motion, substantially as described. 15

In testimony that I claim the foregoing as my invention I affix my signature in presence of two witnesses.

GEORGE N. DOWNS.
